CLAIM

The ornamental design for a surgical tool holder, as shown and described.

DESCRIPTION

FIG. 1 is a view in perspective of a surgical tool holder in upright position;

FIG. 2 is a view in front elevation of the surgical tool holder; FIG. 3 is a view in rear elevation of the surgical tool holder; FIG. 4 is a view in side elevation of one end of the surgical tool holder;

FIG. 5 is a view in side elevation of an end opposite the end shown in FIG. 4;

FIG. 6 is a view in top plan of the surgical tool holder; FIG. 7 is a view in bottom plan of the surgical tool holder; and,

FIG. 8 is a view in perspective similar to FIG. 1 of the surgical tool holder in an alternate position.
